UNITED STATES PATENT OFFICE

2,073,154

METAL STAMPING DEVICE

Gustav Hoffmann, Chicago, Ill.

Application May 9, 1935, Serial No. 20,518

1 Claim. (Cl. 101—29)

This invention relates to metal stamping devices and more particularly to devices for punching identification numbers into machines, castings, bars, etc., of metal.

5 An object of the invention is to provide a device of the kind described which will insure that the die of the stamping device impacts against the material to be stamped in a flat, even manner so as to give a clearly legible stamping.

10 Another object has been to provide efficient indicating means for indicating the die which is in position for stamping, and also means for truing or aligning the die in proper position and keeping it in said position.

15 Another object has been to provide means for positioning the die which will insure the die to be positioned in the proper manner automatically.

Another object has been to provide means for sighting the device with respect to the material to 20 be stamped to ascertain its position with respect to the material.

Another object among others has been to provide a stamping device which will have an efficient punching action.

25 Another object has been to provide a device of the character described which will be durable and efficient, simple in operation and number of parts, and inexpensive to produce.

To accomplish these objects I have provided 30 a device having a standard and a movable die disk in the standard, movably mounted whereby when the entire device is placed on the material to be stamped, a flat, full, and even contact is had between the die and the material to give a 35 highly satisfactory stamping.

These and other objects and advantages will appear more fully hereinafter.

The invention will be best understood by reference to the accompanying drawing forming a 40 part of this specification, in which:

Fig. 1 is an elevational view;
Fig. 2 is an end view;

Fig. 3 is an enlarged view taken on the line 3—3 of Fig. 2;

45 Fig. 4 is a central section of the device shown in Fig. 3; and

Fig. 5 is a detail section taken on the line 5—5 of Fig. 4.

The concrete exemplification which has been 50 selected to illustrate the principle of my invention and its application, includes a base 10, having upwardly extending walls 11 and 12 with elongated slots 13 in the walls. The walls are provided with cut-outs 14 as shown in Fig. 5, 55 providing a horizontal face 15 in each wall and

vertical faces 16. A plunger 17 has legs 18. The legs of the plunger are offset interiorly as at 19, having shoulders 20 to provide an enlarged recess 21 and a reduced recess 22 to accommodate a pawl, as will hereinafter be more fully apparent. 5 The legs 18 are adapted to straddle the walls 11 and 12. The plunger is adapted to reciprocate in the cut-out portions 14, the vertical faces 16 guiding the movement of the plunger. The legs 18 are provided with bores 23 to accommodate a 10 stud 24 which extends also through the slots 13, which stud is also adapted to extend through a bore 25 and a stamping wheel or disk 26. The stud has a cap 27 at one end and at the other end has an annular groove 28 for a spring locking 15 member 29, as shown in Fig. 1.

The stamping wheel or disk 26 on its outer peripheral face 30 has a plurality of raised character dies 31 and notches 32, there being a notch between each pair of dies. Indices 33 are provided on a side of the wheel 26 which may be seen through sight slots 34 in the walls 11 in the base 10. A pin 35 is mounted in the plunger 17 and is connected to a ratchet 36 normally held by a spring 37 in one of the notches 32 to properly position the dies. While the ratchet does not prevent turning when turning is desired to adjust the wheel, the arrangement is sufficient to prevent accidental turning and to maintain the dies in a true or aligned condition. 30

The plunger 17 is normally held in raised position by means of a pair of springs located in the cut-outs 14. Each spring is located between a shoulder 20 and a horizontal face 15 of one of the walls 11 and 12, and also between one of the offset walls 19 and the stamping disk, and also between a pair of vertical faces 16 in one of the walls 11 and 12. By this arrangement each of the 35 springs 38 is bounded and held in position.

The base 10 is provided with an arcuate cut-out portion 39 so as not to interfere with the arcuate wheel when it is hammered down to be stamped and to permit the die to extend therethrough to stamp the material. 40

It will be manifest from the foregoing that the 45 springs 38, abutting at one end against the walls 11 and 12 and with the other end against the plunger, cause the plunger and the wheel to which the plunger is connected through the elongated slot 13 to be normally held in elevated position. 50 The wheel may be turned until the desired die is lowermost and the ratchet will serve to true or align the die. The fact of the true position of the die may be learned from the click of the ratchet in the proper notch and also by attempt- 55

ing to gently move the wheel to see if it locked by the engagement of the ratchet in the groove. The ratchet will also keep the wheel in the desired true position. When it is desired to stamp material, the device may be placed upon the material with its base resting thereon and the entire device may be properly positioned by sighting through the cut-out portion 39 at the base, it being understood also that the sight slot 34 will permit 10 the user to determine what die is in lowermost position. With the device in proper position with respect to the material, it can then be assumed that the die itself is in proper position, and the plunger may be struck with a hammer or other 15 device, and a full, flat, even impact will be had from the die upon the material to be stamped with a highly satisfactory impression.

It will be understood that while I have shown only one wheel, any number of wheels may be 20 used.

The device of my invention has an advantage in respect to safety also, inasmuch as it is not necessary to hold the device in using it. The device may be allowed to rest by itself upon the material to be stamped without any need for holding 25 it, and all that is necessary is to strike the plunger with a hammer.

By means of my device the human element in positioning the die on the material for the hammer blow is entirely eliminated, and a satisfactory 30 result is insured.

While I have shown a particular spring arrangement and a particular arrangement of plunger, etc., it will be understood that my 35 disclosure relates only to one form of my

invention which may take countless other forms.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention what I claim as new and desire to secure by Letters Patent is:

In a metal stamping device, a base having a pair of upwardly extending walls provided with elongated slots and cut out at their upper end to provide a horizontal face and vertical faces in each wall, said base having a foot plate extending beyond the side faces and having a central aperture therein; a plunger having a pair of downwardly extending legs provided with bores and a recess, said legs being adapted to straddle the walls of the base; a stud adapted to extend through the bores in the legs and the elongated slots in the walls for mounting the plunger in the base; a stamping wheel mounted on said stud; and means for normally holding the plunger and stamping wheel in raised position, said means including springs located between the walls of the base and the plunger, said stamping wheel having visible indicia on one side, and one of the walls of the base having a sight slot for sighting said indicia.

GUSTAV HOFFMANN. 35
